GAS-FIRED MUFFLE FURNACE

Malcolm H. Tuttle, New Rochelle, N. Y.

Application March 16, 1946, Serial No. 654,932

3 Claims. (Cl. 263—42)

1

This invention relates to muffle furnaces and aims to provide an improved gas-fired muffle furnace.

The gas-fired muffle furnaces which have been used in the past have included an oven and a heating compartment separated by a partition extending across the top of the oven and through which heat was supplied to the oven. In such furnaces, the fuel is burned at one end of the heating compartment and the heat is supplied to the partition mainly by convection. As a consequence, some portions of the partition are considerably hotter than others and it has not been possible for such a furnace to furnish an even quantity of heat to all parts of the oven. Attempts to get burning of the fuel across the top of the partition have required an excess of oxygen which destroys the partition.

In furnaces requiring intense heat, the partition has consisted of a slab of material such as carborundum which extended across the entire top of the oven. The only points at which such a slab is supported are along its edges. The area which may be covered by such a slab is limited. As the diameter of the slab is increased, its liability to collapse is increased. Attempts have been made to overcome this by increasing the thickness and strength of the slab. In some cases, slabs as thick as 5 inches have been used. However, this is at best a very costly and unsatisfactory expedient and the liability of the partition to collapse has imposed a definite limitation upon the size of past muffle furnaces.

I have discovered that heat may be supplied to the oven of a gas-fired muffle furnace through combined sets of few and relatively inexpensive parts, so that each of these disadvantages of past muffle furnaces is overcome. The sets of parts are capable of being readily combined in such manner that they can supply heat of great intensity uniformly across the entire oven and the number of sets of parts used may be expanded to an extent which, for all practical purposes, renders the size in which the furnace may be built unlimited. The furnace which I have invented is easily assembled and is remarkably economical and efficient in operation.

A muffle furnace constructed in accordance with my invention includes an oven and a battery of radiators. Each radiator has a row of gas burners and a shield of heat-resistant material. The shield is formed in the shape of a trough supported along its side edges to provide a combustion space for its row of burners which is partitioned from the oven. The gas burners of

2

each radiator extend in a row along the trough formed by their shield so that the shield is adapted to radiate heat from those burners into the oven.

5 In order that my invention will be clearly understood, I will describe the specific embodiment of it which is illustrated in the accompanying drawings in which:

Fig. 1 is a transverse section of a furnace embodying my invention;

Fig. 2 is a plan view of the rows of burner units for such a furnace;

Fig. 3 is a section along the lines 3—3 of Fig. 2;

Fig. 4 is a fragmentary view illustrating the 15 mode of assembling the burner units and shield of Fig. 3 to form a radiator; and

Fig. 5 is a view similar to Fig. 3 illustrating a modification in the suspension of the radiators.

The furnace illustrated in Fig. 1 is constructed 20 of a shell 7 of sheet steel which contains floor 8, walls 9 and ceiling 10 of a refractory material such as fire brick to provide an oven 11. A battery of radiators 12 is suspended from the ceiling 10 and is adapted to direct intense heat 25 downwardly into the oven.

Each radiator 12 consists of a row of burner units 14 and a thin shield 15 of heat-resistant material. The area bounded by the row of burner units 14 and the shield 15 constitutes the combustion space 16 of radiator 12. The burner unit 14 includes a nozzle 17 and a refractory ceramic core 19 having a cup-shaped opening 20 which surrounds the lower end of nozzle 17. A square base 22 of a refractory material such as carborundum supports the core 19. The burners are operated on a mixture of air and a combustible gas, such as illuminating gas, supplied by pipes 23 and 24 respectively. The richness of the mixture is controlled by valves 25 and 26.

40 The gas and air mix in conduit 28 and then flow through manifold 30. The nozzles 17 are connected with manifold 30 by conduits 32. Products of combustion flow from the combustion spaces 16 through ducts 34 and exhaust manifold 35 to the exhaust stack 36.

The shield 15 is formed in the shape of an elongated trough whose side edges are turned inwardly to form flanges 37. Slots 38 are formed in the sides of each base 22 to receive the flanges 50 37. The composition of the shield 15 depends upon the degree of heat to be supplied to oven 11. For example, when the temperature in combustion space 16 is maintained at about 2000° F., shield 15 is formed from a sheet of alloy steel which is about $\frac{1}{8}$ of an inch in thickness, con-

tains about 55% iron, 25% chromium and 20% nickel, and is an excellent conductor of heat. When extremely intense heat is required in oven 11, the shield is formed from a material such as carborundum which, although not such a good conductor, will withstand heat of greater intensity.

The burner units 14 illustrated in Figs. 1, 3 and 4 are individually suspended from the ceiling 10 by means of beams 39, 40 attached to that ceiling and T-bolts 41 whose heads 42 are adapted to fit into the grooves 43 provided for them in base 22. The shield 15 is supported by its row of burner units 14 through engagement of flanges 37 with the bottom surface of slots 38. The shield 15 is thus supported at each side along its entire length and, since it is comparatively narrow, it is possible to fabricate that shield from a thin sheet of heat-resistant material.

It will be noted that the burner units 14 of each row are contiguous and that the radiators 12 are spaced very closely together so that they cover substantially all of ceiling 10. Consequently, heat can be supplied uniformly along the entire top of the oven. Nevertheless, the radiators 12 may be assembled easily. It is possible also, to effect repairs on those radiators with a minimum of effort. To do this, it is necessary merely to slide the shield 15 away from its row of burner units 14. Then any of those burner units may be removed for repair or replacement without disturbing the other burner units. Furthermore, the number of burner units 14 in a row and the number of radiators 12 may be expanded as required to construct a furnace of any desired size.

The radiators 12 are remarkable for the efficiency with which they transfer heat to oven 11. Combustion in space 16 heats the inner faces of the burner units 14 to incandescence. The shields 15 are then heated by radiant heat from those faces. Heat so supplied to the thin shields 15 is radiated by them in turn to the oven 11. The intensity of that heat may be governed by regulation of valves 25 and 26. Combustion of the gas is complete and there is no excess of oxygen which could destroy shield 15.

The radiators 44 which are illustrated in Fig. 5 operate in the same way as the radiators 12 but they are suspended from the ceiling of the furnace in a somewhat different manner. Each burner unit 45 is individually suspended from the furnace ceiling by means of hangers 46 which are attached to the ceiling beams 47. The lower end of hanger 46 is provided with a pair of flanges 48 whose ends 49 are returned toward each other to form channels. Slots 50 are formed in the base 51 of the burner unit to receive the flanges 48. The shields 52 are supported through engagement of their flanges 53 with the ends 49. By this construction, the form of the burner blocks 51 is simplified somewhat since the grooves 43 are omitted, and, since the flanges 53 do not come in contact with the burner blocks 51, chipping of those burner blocks may be reduced.

The furnace which I have invented is adapted for use in the heat treatment of a wide variety of materials, particularly where such heat treatment is to take place in a non-oxidizing atmosphere. It is known that, in the heat treatment of some materials, special conditions are imposed which will necessitate changes in the specific embodiment of my invention which I have described, and it is to be understood that various modifications may be made in that embodiment without departing from the spirit of my invention as defined in the appended claims.

What I claim is:

1. A muffle furnace comprising an oven and a battery of radiators covering substantially all of the top of the oven and adapted to direct heat downwardly into said oven, each of said radiators having a combustion space, a row of gas burners communicating with the combustion space and having slotted sides, a removable trough-shaped shield partitioning the combustion space from the oven and having flanges extending inwardly from its sides adapted to fit in the slots in said burners, and detachable hangers suspending said burners from the top of the furnace so that any one of them may be removed independently of the others.

2. A muffle furnace comprising an oven and a battery of radiators covering substantially all of the top of the oven and adapted to direct heat downwardly into said oven, each of said radiators having a combustion space, a row of gas burners having slotted sides and a removable shield partitioning the combustion space from the oven and having flanges extending inwardly from its sides; and detachable hangers having channeled ends adapted to fit in the slots in said burners and to contain the flanges on said shields.

3. A muffle furnace comprising an oven and a battery of radiators covering substantially all of the top of the oven and adapted to direct heat downwardly into said oven, each of said radiators having a combustion space, a row of gas burners communicating with the combustion space and having grooved and slotted sides, a removable trough-shaped shield partitioning the combustion space from the oven and having flanges extending inwardly from its sides adapted to fit in the slots of said burners, and detachable hangers adapted to fit in the grooves in said burners and suspending said burners from the top of the furnace so that any one of them may be removed independently of the others.
